BODY AND FENDER TOOL

Harold P. Hartman, Terre Hill, Pa.

Application May 22, 1947, Serial No. 749,767

2 Claims. (Cl. 153—32)

1

This invention relates to body and fender tools, particularly to pneumatically operated tools of this type which include opposed members adapted to engage the opposite faces of an intermediate metal sheet and at least one of which is adapted to be vibrated at high frequency.

Tools of this general type and suited for use in straightening and smoothing bent or crumpled automobile fenders or body panels are now in widespread use. In each instance such a tool includes opposed work engaging members, commercially known as "dollies," together with a frame upon which the dollies are mounted and upon which is supported a means for effecting the vibration at relatively high frequency of at least one of the dollies, the moving dolly being in the nature of a hammer, delivering blows of low amplitude but high frequency against the work, and the opposed dolly being in the nature of an anvil supporting the sheet under the repeated blows of the moving dolly. By moving the tool progressively along a crumpled area successive areas thereof are subjected to its action and eventually the sheet is brought into smooth condition and given the desired contour.

Heretofore, however, it has been generally found necessary, after a sheet such as an automobile fender has been subjected to the action of such a tool, to smooth that surface which is to be subsequently painted with a file prior to the actual application of the paint or enamel. This is because the vibrating dolly, even when most skillfully used, leaves flat imprints upon the metal being treated and, even though these flat imprints are of relatively small area individually, they may, nevertheless, be observed even after the application of paint, thus necessitating the use of an abrading tool to produce a smooth rounded surface which will have the appearance of one which has not been injured. Prior tools of this general nature have likewise been deficient in that even the best of them will occasionally catch against a protuberance on the surface over which it is moved and will sometimes put nicks in the sheet metal being straightened and smoothed. Fender tools of the prior art have also been so designed and constructed that fairly satisfactory results may be obtained only after the operator has had long experience in its use, rather poor results being obtained when the tool is in the hands of an operator without such experience.

The improved body and fender tool, a pre-

2

ferred embodiment of which is illustrated in the accompanying drawings and will be hereafter described in detail, has a substantially improved ability to work damaged metal sheets into desired contour and surface smoothness. Two opposed dollies are provided, as heretofore, but one of them, preferably the vibrating dolly, is so designed and constructed that its work engaging face is discontinuous and comprises, instead of a smooth flat or gently rounded surface, a plurality of spaced, relatively small, rounded work engaging elements adapted to simultaneously strike the face of the metallic sheet to be straightened and to be simultaneously lifted from the surface of the work when the direction of the movement of the dolly is reversed. A sheet intermediate the opposed dollies, upon being struck simultaneously by a substantial number of the rounded work engaging elements of the moving dolly, will be beneficially worked over a considerable area and the necessary straightening force exerted thereon. At the same time the effect upon the sheet is materially different from the effect realized when a dolly of the prior art is in use, each impact leaving a regular series of spaced rounded shallow indentations in the metallic surface instead of a single, relatively large and generally flat surface as heretofore.

It is found that a body and fender tool employing a dolly of the improved type above briefly described will remove creases in the crumpled metal in a superior manner, is more effective in the lifting of low spots in the metal and bringing all areas thereof to the desired contour and that, as a result of its use, large areas of damaged or crumpled metallic sheet may be so perfectly restored to its original contour as to be ready for the application of paint immediately upon the completion of the shaping operation, no further mechanical preparation of the surface for the reception of paint, as by filing, being necessary. The improved tool will not put nicks in the metal being subjected to its action and may be moved readily and rapidly over its surface without catching. It is of most durable nature and may be readily kept in perfect operating condition.

Preferably I employ, for the purpose of providing the vibrating dolly with a plurality of separately formed spaced rounded work engaging elements which together comprise a discontinuous work engaging surface, a series of hardened steel balls, such as ball bearings, and in one form of the invention primarily intended for use in the straightening of fenders and automobile body

panels, balls one-eighth inch in diameter have been found eminently suitable. These balls are preferably arranged in a regular series or pattern and are retained upon the vibrating dolly by means which permits them to contact with the work but which nevertheless maintains them in predetermined relative positions. The novel dolly preferably includes a body and cap, the body and cap together defining a plurality of ball receiving and retaining recesses. The body is of such character as to be readily applicable to the standard body and fender tool. Means is provided for facilitating the cleaning of the tool and, in the preferred embodiment of the invention, ducts passing entirely through the body have their inlet ends in communication with the recesses, respectively, in which the hardened steel balls are housed. After the dolly has been in use for some time fluid, such as compressed air or a cleaning solution, may be forced through the dolly, being preferably first passed through the several ball receiving recesses, which are not completely blocked by the balls which they contain, and thereafter passing through ducts or conduits leading from these recesses to discharge ports in opposite faces of the body. The specific details of design may be changed in various ways without departure from the invention but I prefer to employ dollies of the type described, comprising hardened steel balls and suitable means for retaining them in spaced relation upon the body of the dolly so that they together constitute a series of rounded work engaging elements which constitute a discontinuous work engaging surface. In some instances, however, the rounded work engaging elements may be formed integral with the body of the dolly. It is possible to utilize various styles of separately formed work engaging elements and to secure them to the body of the dolly in various ways.

In the drawings, in which there is illustrated a preferred form of the invention by way of example,

Figure 1 illustrates in section a small portion of a metal sheet to be straightened and shows in side elevation the opposed dollies which comprise the work engaging members;

Figure 2 is an enlarged view of the face of the vibratory dolly, portion of the cap being broken away so that the face of the body of the dolly may be clearly perceived;

Figure 3 is a section on line 3—3 of Figure 2;

Figure 4 is an enlarged section through portion of the dolly, showing a few of the work engaging elements and more clearly disclosing adjacent portions of cap and body.

Figure 5 is a view generally similar to Figure 2 showing the rear of a modified form of the dolly; and

Figure 6 is a section on line 6—6 of Figure 5.

The body of the dolly illustrated in Figures 1 to 4 inclusive includes a forward portion in the nature of an annular disc 10 and a stem 11 which is generally cylindrical in shape, the stem and disc 10 being preferably formed from one piece of metal. The forward face of the disc 10 is provided with a concentric series of annular grooves 12, 13, 14, 15, 16 and 17 respectively and the lands or circular ridges intermediate these grooves comprise seating members against which the work impacting elements are adapted to rest. The work engaging elements are, in the form of the invention disclosed, hardened steel balls 18 and these balls are disposed in concentric rings as clearly shown in the drawings, with a single ball

18a occupying the central position and engaging the central ball supporting land, which is encircled by the annular groove 12.

The balls are retained in the positions in which they are shown by means of a cup shaped member or cap 20 which is provided with a plurality of ball receiving recesses, several of which are most clearly shown in Figure 4 and indicated at 21. The diameter of each opening 21, at the rear face 10 of the cap and for approximately half of its length is slightly greater than the diameter of the ball which is housed therein but each recess, as may be clearly observed in Figure 4, has a forwardly and outwardly tapering spherical socket portion 21a which terminates in a circular opening 21b formed in the forward face of the cap. The thickness of the cap is such that, when it is positioned as shown in Figures 3 and 4, each ball will be retained in a ball receiving recess which is just sufficiently large to provide a snug housing for the ball, which may not escape nor move materially, being laterally confined by the circular wall of the recess, prevented from moving forwardly because of its engagement with the spherical retaining surface 21a, and may not move rearwardly because of its engagement with the surface of the associated land of the body of the dolly. Because of the fact that the diameter of each ball is slightly less than the diameter of the recess in which it is received, the ball may turn when the instrument is in use. The slight clearance between each ball and the wall of the recess in which it is confined also permits fluid under pressure to be forced through the several apertures in the face of the cap and around the ball and into the adjacent grooves, for instance grooves 14 and 15 shown in Figure 4, from which grooves the fluid may pass into ducts, such as indicated at 22, and led to the rear faces of disc 10 and stem 11 of the dolly. Suitable means for forcing liquid or gas under pressure may be provided and a cleaning operation may be effected very quickly in this manner, a liquid solvent being passed through the dolly in the event that the ball receiving recesses contain grease or other soluble material which might tend to interfere with the freedom of movement of the balls.

The invention contemplates the utilization of dollies in which the discontinuous work engaging surfaces are not only flat, as disclosed in Figures 1 to 4 inclusive, but convex, a dolly having a convex discontinuous work engaging surface being shown in Figures 5 and 6. In this form of the invention the active face of the dolly is elongated, being preferably oval in shape, and the axis of the stem 11 is offset from the axis of the integral duct portion 10¹ of the dolly. The ball retaining cap 20¹ is convex, as illustrated, but the several balls are retained as before in recesses defined in part by the cap and in part by the lands intermediate grooves 12¹, 13¹, 14¹ and 15¹ formed in the convex forward face 10¹ of the body. A dolly so formed with discontinuous convex surfaces, is particularly suitable for use in the straightening of fenders which have been seriously damaged and the dolly in such use may be tilted to various angles as it is advanced over the work. Other forms of the invention may be devised to suit special circumstances.

Having thus described the invention, what is claimed as new and desired to be secured by Letters Patent is:

1. A dolly for a body and fender tool adapted to be vibrated at high frequency when in contact with a sheet metal member to be smoothed, said

dolly having a ball supporting base and a ball retaining and spacing cap secured to the base in ball retaining position, portions of the balls extending beyond the cap to form a discontinuous metal working surface, and ducts formed in and passing through the said base to communicate with the ball receiving recesses, whereby fluid under pressure may be forced into said recesses.

2. A dolly of the class described comprising a base having a plurality of seating surfaces for a plurality of hardened steel balls disposed substantially in a plane, and a perforated cap secured to the base, the balls being confined by the cap and seating surfaces of the base, a portion of each ball projecting through a perforation in the cap and the several such projecting portions together comprising a discontinuous work engaging surface, the said base being provided with a plurality of ducts passing entirely therethrough, one end of each duct opening into the ball con-

fining space, whereby fluid under pressure may be forced into the said recesses.
